UNITED STATES PATENT OFFICE.

JOHN ZIMMERMAN, OF CHICAGO, ILLINOIS, AND FREDERICK L. WHITE,
OF WATERBURY, CONNECTICUT; SAID WHITE ASSIGNOR TO SAID
ZIMMERMAN.

DESIGN FOR A VEHICLE-LAMP.

SPECIFICATION forming part of Design No. 28,593, dated May 10, 1898.

Application filed June 18, 1897. Serial No. 641,364. Term of patent 7 years.

To all whom it may concern:

Be it known that we, JOHN ZIMMERMAN, residing at Chicago, in the county of Cook and State of Illinois, and FREDERICK L. WHITE, residing at Waterbury, in the county of New Haven and State of Connecticut, have invented and produced a new and original Design for Vehicle-Lamps, reference being had to the accompanying drawings, forming a part hereof.

In the accompanying drawings, Figure 1 is a side elevation of a lamp, showing the form in which our design is embodied; and Fig. 2, a front elevation thereof.

The leading feature of our design consists substantially in a circular base portion arranged with the plane of the circle in a horizontal plane, a vertical circular body portion

with its plane arranged in a vertical plane, a rear perforated portion, and a small circular top portion.

A is the circular base portion, arranged in a horizontal plane; B, the circular body portion, arranged in a vertical plane; C, the rear perforated portion, and D the circular top portion, the whole presenting to the eye a harmonious and ornate figure, as shown in the accompanying drawings.

We claim—

A design for a vehicle-lamp, substantially as herein shown and described.

JOHN ZIMMERMAN.
FREDERICK L. WHITE.
